Des. 225,992
Patented Jan. 16, 1973

225,992

PHARMACEUTICAL TABLET

Theodor Langauer, Muttenz, Basel, Switzerland, assignor
to Ciba-Geigy AG, Basel, Switzerland

Filed Sept. 29, 1969, Ser. No. 19,330

Term of patent 14 years

Int. Cl. D28—01

U.S. Cl. D16—3

FIG. 1 is a top view of the tablet embodying my new design;

FIG. 2 is a right side view thereof;

FIG. 3 is a cross-sectional view through line 3—3 of FIGS. 1 and 5 thereof;

FIG. 4 is a bottom view thereof; and

FIG. 5 is a top plan view of a modified embodiment of the tablet disclosed in FIG. 1, the bottom being a mirror image of the tablet shown in FIG. 4.

I claim:

The ornamental design for a pharmaceutical tablet, substantially as shown and described.
